ATTORNEY

UNITED STATES PATENT OFFICE

NELSON CHRISTENSEN, OF BROOKLYN, NEW YORK, ASSIGNOR TO INTERNATIONAL CIGAR MACHINERY COMPANY, A CORPORATION OF NEW JERSEY

AUTOMATIC CIGAR HANDLING DEVICE

Application filed November 20, 1930. Serial No. 497,050.

This invention relates to automatic cigar handling devices, its main object being to transfer a cigar from one place to another and at the same time to turn it at an angle to its vertical axis. With this and other objects not specifically mentioned in view, the invention consists in certain constructions and combinations which will be hereinafter fully described and then specifically set forth in the claims hereunto appended.

In the process of manufacturing and boxing cigars, it is continually necessary to transfer the cigars from one position to another and when the respective positions are at right angles to one another, the cigar must be swung around about its vertical axis in transit, usually with the additional condition that it must not be turned circumferentially while being transferred.

In the present invention, this object is accomplished by a swinging arm carrying rotatably mounted clamping fingers which turn the cigar through an angle while the swinging arm transfers the same. The swinging arm is operated by means of a suitably driven cam and carries the cigar directly above a guide into which the cigar is discharged and in which it is advanced by a pusher operated by a rack and gear construction. In repeating the operation the preceding cigar is pushed forward and delivered into a gripper carried by the receiving apparatus which in the case illustrated is the turret of a banding machine which is thus automatically fed from a cigar enveloping machine placed at an angle to the former.

In the accompanying drawing which form a part of this specification and in which like characters of reference indicate the same or like parts:

Fig. 1 is a side elevation of the cigar turning transfer; and

Fig. 2 is an end elevation of the same.

In carrying the invention into effect, there is provided a support for cigars, a guide on the support, means for transferring cigars from the support to the guide and turning them about their own vertical axes in transit, and means for moving the cigars along the

guide. In the best constructions contemplated, the transferring means includes a swinging arm and clamping fingers rotatably mounted on the swinging arm, and the means for moving the cigars along the guide includes a pusher connected to a reciprocating rack. These various means and parts may be widely varied in construction within the scope of the claims, for the particular device selected to illustrate the invention is but one of many possible concrete embodiments of the same. The invention, therefore, is not to be restricted to the specific construction shown and described.

The base 10 of the enveloping machine carries frames 11 and 12, the latter supporting a plate 13. The frames 11 carry a cross shaft 14 on which is fastened a gear 15 meshing with a gear 16 turning on stud 17, the gear 16 being combined with a cam 18. The cam 18 on turning actuates an arm 19 by means of a cam roller 20 mounted on a stud 21. The arm 19 is pivoted on a stud 22 fastened to a bracket 23 attached to base 10, and is joined to a link 24 by a stud 25. The link 24 carries a stud 26 engaging a slot in the arm 27 fastened to a hollow rock shaft 28 mounted in bearings 29 and 30 attached to base 10. Fastened to shaft 28 is a gear segment 31 adjacent a stationary arm 32 attached to bearing 29, the arm 32 carrying a stud 33 on which turns a gear 34 meshing with segment 31. To the gear 34 is attached a gear 35 which meshes with a rack 36 slidably mounted on the frame 13 and operating a pusher 37. A swinging arm 38 is also fastened to the hollow shaft 28 for a purpose hereinafter described. To the bearing 30 is attached a sprocket 39 which by means of a chain 40 and a sprocket segment 41 imparts a rocking motion to a shaft 42 carried by a sleeve 43 attached to swinging arm 38, as the latter swings back and forth. The sprocket segment 41 has its lower edge formed as a straight line below its centre as shown in Fig. 1. On the cross shaft 14 is mounted a sprocket 44 driving through chain 45 a sprocket 46 turning on shaft 28 for a purpose hereinafter described. The chain may be kept in tension by a gravity idler 100.

sprocket engaging its upper run as in Fig. 1.

The operation of the mechanism is as follows:

The gear 15 which is driven from the main shaft of the enveloping machine, meshes with the gear 16 and turns the cam 18 which actuates the arm 19 and moves it to the dotted position 19', thereby bringing the arm 27 into position 27'. In the meanwhile, the wrapped cigar C which has been discharged from the turret T of the enveloping machine rests on the plate 13 where it is gripped by the clamping fingers 47 and 48. The clamping finger 47 is fastened to the head 49 of a shouldered stud 50 while the clamping finger 48 is mounted on a movable arm 51 pivoted on the head 49. The stud 50 which carries the bevel gears 52 and 53 is held in head 54 of shaft 42. Bevel gear 53 meshes with gear segment 55 attached to sleeve 43 which supports shaft 42. Inserted into the ends of the sleeve 43 are the bushings 56 in which revolves the shaft 42.

The object of providing the bevel gear 52 is to enable the cigar C to be turned about its vertical axis in the opposite direction so that the proper end of the cigar can be inserted into the banding machine gripper in case the cigar is delivered by the enveloping machine in the reverse position from that shown in the drawing. To set the transfer for the reverse position of the cigar, it is only necessary to turn sleeve 43 in arm 38 by 180 degrees so that the gear segment 55 then meshes with gear 52 instead of gear 53, thereby reversing the direction of motion of stud 50.

In moving from position 27 to position 27', the arm 27 turns the rock shaft 28 thereby moving the swinging arm 38 into the dotted position 38'. The motion of arm 38 causes the chain 40 to rotate the sprocket 41 which turns the shaft 42, maintaining the stud 50 in substantially vertical position and causing the gear 52 or 53 to roll on the gear engagement 55, which rotates the stud 50, and thereby swings the cigar at right angles to its axis as shown in the dotted position. The cigar, on having reached this point, is released from the clamping fingers 47 and 48 by means hereinafter described.

The movable arm 51 is fixed on a rod 57 loosely mounted in the head 49 and carrying on one of its upwardly bent ends a roller 58 which comes into engagement with a stationary cam piece 59 and thus swings the finger 48 away from the cigar C, thereby allowing the latter to drop into the guide 60 in which it is pushed forward by the plunger 37 attached to rack 36 while being held down by a flat spring 61 fastened to bracket 62 attached to plate 13. When the roller 58 leaves the cam piece 59, a spring 63 wound around the rod 57 and fastened thereto at one end 65 and fastened at its other end to a pin 64 car-

ried by the head 49, causes the finger 48 to close. In the meanwhile the sprocket 44 driven by gear 15 has turned the sprocket 46 which carries a cam 65, the latter thus coming into engagement with a cam roller 66 on a stud 67 in block 68 on shaft 69 which latter is loosely fitted into the hollow shaft 28. Therefore, when the cam 65 engages with the roller 66, the block 68 is moved into position 68' and in doing so, it moves the pin 70 carried by shaft 69 and sliding in a slot 71 of shaft 28 into the dotted position 70'. The pin 70 in this position trips on arm 72 pivoted on stud 73 carried by the hub 74 of arm 38. The other end of arm 72, by a stud 75, is pivoted to a link 76 attached to stud 77 of arm 78 swinging on a pin 79 held by a projection 80 of arm 38. Fastened to the arm 78 is a rod 81. The tripping of arm 72 causes the rod 81 to move downwardly to engage with a roller 82 on rod 57, thereby opening the movable finger 48 which then is ready to grip the next cigar discharged from the turret T. The forward movement of the cigar C by the pusher 37 causes the preceding cigar C' delivered to the guide 60 to be pushed into gripper G of the banding machine.

What is claimed is:

1. In a cigar handling device, the combination with a support for cigars, of a guide on said support arranged to deliver the cigars to a cigar banding machine, means for gripping the mid-section of cigars and transferring them from said support to said guide and turning them about their own vertical axes in transit, and a device for moving the cigars along said guide, said means including a rock shaft, an arm secured to said rock shaft, a stud rotatably mounted on said arm, a stationary clamping finger fixed on said stud, a movable clamping finger pivoted on said stud, a spring connected to said movable finger and normally causing it to close, means for opening said movable finger to engage a cigar on said support, mechanism for turning said shaft, whereby to swing said arm to carry said cigar to a position overlying said guide, gear means for rotating said stud to align said cigar with said guide, and cam means for opening said movable finger to permit said cigar to drop into said guide.

2. In a cigar handling device, the combination with a support for cigars, of a guide on said support arranged to deliver the cigars to a cigar banding machine, means for gripping the mid-section of cigars and transferring them from said support to said guide and turning them about their own vertical axes in transit, and a device for moving the cigars along said guide, said means including a movable arm, mechanism for moving said arm, relatively movable clamping fingers connected to said arm, mechanism for relatively closing said fingers on a cigar, and

mechanism for relatively opening said fingers to release said cigars.

3. In a cigar handling device, the combination with a support for cigars, of a guide on said support arranged to deliver the cigars to a cigar banding machine, means for transferring cigars from said support to said guide and turning them about their own vertical axes in transit, and a device for moving the cigars along said guide, said means including a rock shaft, and said device including a pusher, a rack connected to said pusher, and a gear connected to said rock shaft and engaging said rack.

4. Means for transferring cigars, comprising a rock shaft, an arm secured to said rock shaft, a normally vertical stud rotatably mounted on said arm, a stationary clamping finger fixed on said stud, a movable clamping finger pivoted on said stud, a spring connected to said movable finger and normally causing it to close, means for opening said movable finger to engage a cigar, mechanism for turning said shaft, whereby to swing said arm to carry said cigar to delivery position, gear means for rotating said stud to turn the cigars about their own vertical axes in transit, and cam means for opening said movable finger to release said cigar.

5. Means for transferring cigars, comprising a rock shaft, an arm secured to said rock shaft, a stud rotatably mounted on said arm, a stationary clamping finger fixed on said stud, a movable clamping finger pivoted on said stud, a spring connected to said movable finger and normally causing it to close, means for opening said movable finger to engage a cigar, mechanism for turning said shaft, whereby to swing said arm to carry said cigar to delivery position, gear means for rotating said stud, and cam means for opening said movable finger to release said cigar, said means for opening said movable finger 45 to engage a cigar including a roller connected to said movable finger, linkage carried by said arm and arranged to engage said roller to open said movable finger, a shaft slidably mounted in said rock shaft, and a cam on said rock shaft for actuating said slideable shaft to engage said pin with said linkage.

6. Means for transferring cigars, comprising a rock shaft, an arm secured to said rock shaft, a normally vertical stud rotatably mounted on said arm, a stationary clamping finger fixed on said stud, a movable clamping finger pivoted on said stud, a spring connected to said movable finger and normally causing it to close, means for opening said movable finger to engage a cigar, mechanism for turning said shaft, whereby to swing said arm to carry said cigar to delivery position, gear means for rotating said stud to turn the cigars about their own ver-

tical axes in transit, and cam means for opening said movable finger to release said cigar, said mechanism including a cam connected to said rock shaft.

7. Means for transferring cigars, comprising a rock shaft, an arm secured to said rock shaft, a stud rotatably mounted on said arm, a stationary clamping finger fixed on said stud, a movable clamping finger pivoted on said stud, a spring connected to said movable finger and normally causing it to close, means for opening said movable finger to engage a cigar, mechanism for turning said shaft, whereby to swing said arm to carry said cigar to delivery position, gear means for rotating said stud, and cam means for opening said movable finger to release said cigar, said gear means including a gear fixed on said stud, a shaft carried by said arm, a gear segment engaging said gear and carried by said shaft, a sprocket fixed on said shaft, a stationary sprocket and a chain connecting said sprockets, whereby swinging of said arm will rotate said stud.

8. Means for transferring cigars, comprising a rock shaft, an arm secured to said rock shaft, a stud rotatably mounted on said arm, a stationary clamping finger fixed on said stud, a movable clamping finger pivoted on said stud, a spring connected to said movable finger and normally causing it to close, means for opening said movable finger to engage a cigar, mechanism for turning said shaft, whereby to swing said arm to carry said cigar to delivery position, gear means for rotating said stud, and cam means for opening said movable finger to release said cigar, said cam means including a roller connected to said movable finger and a stationary cam piece arranged to engage said roller when the cigar is in delivery position.

9. Means for transferring articles, comprising a movable arm, means for moving said arm to delivery position, relatively movable clamping fingers, a support for said fingers rotatably mounted on said arm, means for causing said fingers to engage an article, means for relatively opening said fingers to release the article when said arm reaches delivery position, and mechanism for rotating said support to turn the article in transit, said support including a sleeve rotatably mounted in said arm, a stud rotatably mounted in said sleeve, and said mechanism including gears fixed to each end of said stud, a shaft mounted in said arm, a gear segment secured to said shaft and adapted to engage either of said gears to rotate said stud in opposite directions, a sprocket secured to said shaft, a stationary sprocket, and a chain connecting said sprockets.

10. Means for transferring articles, comprising a movable arm, means for moving said arm to delivery position, relatively movable clamping fingers, a support for said fin-

gers rotatably mounted on said arm, means for causing said fingers to engage an article, means for relatively opening said fingers to release the article, when said arm reaches delivery position, and mechanism for rotating said support to turn the article in transit, said means for causing said fingers to engage the article including a linkage, a movable shaft, a pin carried by said shaft and adapted to engage said linkage, and a cam arranged to move said shaft, whereby to actuate said pin.

11. Means for transferring articles, comprising a movable arm, means for moving said arm to delivery position, relatively movable clamping fingers, a support for said fingers rotatably mounted on said arm, means for causing said fingers to engage an article, means for relatively opening said fingers to release the article when said arm reaches delivery position, and mechanism for rotating said support to turn the article in transit, said means for relatively opening said fingers to release the article including a roller connected to one of said fingers and a stationary cam piece adapted to engage said roller when said arm reaches delivery position.

In testimony whereof, I have signed my name to this specification.

NELSON CHRISTENSEN.
